UNITED STATES PATENT OFFICE.

FRANK HINMAN PIERPONT, OF HORLEY, ENGLAND, ASSIGNOR TO LANSTON MONO-TYPE MACHINE COMPANY, OF PHILADELPHIA, PENNSYLVANIA, A CORPORATION OF VIRGINIA.

TYPOGRAPHIC COMPOSING-MACHINE.

1,079,361.

Specification of Letters Patent. Patented Nov. 25, 1913.

Application filed June 3, 1912. Serial No. 701,323.

To all whom it may concern:

Be it known that I, FRANK HINMAN PIERPONT, a citizen of the United States, residing at Horley, in the county of Surrey, England, have invented a certain new and useful Improvement in Typographic Composing-Machines; and I do hereby declare the following to be a full, clear, and exact description of the same, reference being had 10 to the accompanying drawings and to the figures and letters of reference marked thereon.

This invention relates to key-operated or manually controlled typographic composing 15 machines of the kind for producing or composing a pattern, record strip or other governing element of an automatically controlled composing or type-casting and composing machine.

20 The chief object of the invention is to expedite or simplify the composition of tabulated matter on such machines.

In these machines, examples of which are to be found in the specifications of British 25 Letters Patent Nos. 18,638/99, 15545/06 and 17199/08 (U. S. Patents No. 654,115 of July 17, 1900; No. 828,449 of August 14, 1906 and No. 944,405 of Dec. 28, 1909) composition is effected by the manipulation of keys 30 representing characters, spaces and justification fractions, and adapted, through permutation or equivalent mechanism, to actuate punches or other signal producing devices operating to compose or produce the 35 pattern or record-strip.

In order that the composed lines may be produced justified, these machines are provided with measuring and indicating mechanism for designating the justification signals required to be added to the pattern for 40 a particular line of composition in order that the line of typographic matter may be produced justified in the automatic machine.

This measuring mechanism comprises a 45 measuring member advanced step by step a certain distance corresponding to the unit value of the signal denoted by the successive keys as operated, a second measuring element advanced, on the operation of a special key, to meet the first measuring element and thereby effect the setting of a justification chart or indicator operatively connected with and positioned by the second measuring element.

50 The compositor operates the keys, which

produce signals denoting type, both with respect to character and dimension, until the composition approaches the end of a line, which approach is notified usually by an audible signal, then if the line is not exactly 60 filled and all the matter that be included properly has been included, the compositor, by operating one special key to effect the setting of the justification devices, can observe from the indicator, the justification 65 required and thereafter strike the appropriate key or keys to produce the required signal or signals for the line. After this, he operates a re-setting key by which power is withdrawn from the motor driving the line 70 measuring element and power admitted to a reversing motor for re-setting the line measuring element.

The justification indicating mechanism, which in some form is common to all such 75 composing machines, is operative, properly speaking, only near the end of a line, and within a predetermined area known as the justification area, the entrance of the composition into which is notified by the sounding of a bell or by some other signal, and after justification has been performed the measuring mechanism is returned or reset, for the commencement of the composition of a fresh line, by the operation of a re-setting 80 mechanism controlled generally by a key. The extent of the return movement is determined by a fixed zero stop previously set to the commencing point for a full measure 85 of straight composition. This mechanism 90 therefore answers, exceedingly well, all the requirements of composition of straight forward matter, but when it is required to compose tabular matter wherein a full measure 95 or complete line is comprised of two or more sections each existing as a separate entity so far as justification is concerned, then the compositor has to rely on artificial methods and artifices for obtaining the justification 100 of each section. These methods, which are rendered possible by the skill and knowledge of the compositor, increase the possibility of error and interrupt the attention of the operator to his composition.

According to the present invention, a 105 variable stop mechanism is provided whereby justification of the various sections in a complete line can be effected with the same facility and rapidity as with a line of full measure, hitherto.

The invention is particularly applicable to the method of composing tabular matter on these machines, wherein in order to obtain the assistance of the justification devices for each section, composition of each of the sections is made to finish within the existing justification area. In order to render this possible hitherto the zero stop has been set for the commencing point of the largest section or minor line in the full line and, for composing the other sections, when the re-setting key has been operated, the return movement of the measuring element has been controlled by hand or otherwise manipulated to proper position. This method necessitates the compositor remembering which section he is about to commence, subtracting the units comprised in that section from those of the largest section (for which the zero stop remains set) and setting the measuring element accordingly. With the present invention all this is avoided. This mechanism comprises a series of adjustable zero stops for the measuring element, the members of which are automatically and separately interposed in, and withdrawn from, the return path of the measuring element to form the zero stop or, in other words, establish datum lines, for the commencement of the successive sections of the line.

The stops according to this invention are adjustably carried upon a rotary shaft or member, and are set or adjusted by or in consequence of the initiation of the return or resetting movement of the measuring mechanism controlled preferably by the actuation of the re-setting key. Automatic mechanism which is adjustable, is provided for returning or allowing the shaft to return to zero position after the stops of the series have been in operation, under the influence of a motor, preferably a spring, for the commencement of a new line. Conveniently the mechanism is so contrived as to effect the movement or adjustment of the stop in advance of the return of the measuring element.

Referring to the accompanying drawings wherein the invention is shown applied to a composing machine of known construction Figure 1 is a front elevation partly in section of mechanism embodying the invention as shown in position on a composing machine of known construction. Fig. 2 is a plan of Fig. 1. Fig. 3 is an end elevation of Fig. 1. Fig. 4 is a sectional end elevation of Fig. 1 showing the parts at a different point in the cycle of operations from Fig. 3. Figs. 5 and 6 are also sectional end elevations of the mechanism. Fig. 7 is a sectional end elevation on the line 7-7, of Fig. 1. Fig. 8 is a section on the line 8-8, of Fig. 2, and Fig. 9 is another end sectional elevation.

The same reference characters denote the same parts throughout the drawings.

A A' A² are the stops.

B is the rotatable shaft carrying the stops.

C is the spring motor by which the shaft 70 is returned to initial position.

D is the mechanism for advancing the shaft to interchange the stops, and E is the controller or mechanism for controlling the return of the shaft to initial position.

The stops A of which there may be any appropriate number, are adjustable both longitudinally and circumferentially of the shaft B, which latter is advanced at each operation of the special key, to interpose 80 the stop for the next section to be composed and withdraw the one previously in use until all the stops required have been used. The shaft is then returned to initial position through an adjustable controller E which 85 renders the forward driving mechanism inoperative, releases a holding device and allows the return motor C to return the shaft B.

The shaft B is furnished or cut with a 90 series of annular grooves B' at equal distances apart, conveniently 18 units and the stops A A' A², which are formed with an opening conveniently oval in form embracing the shaft, are each provided with a key or eccentric rib a to fit into one of the grooves. In the shaft B are also cut a series, conveniently 95 twelve, of longitudinal grooves or slots B² into one or other of which an adjustable key a' with which each stop is furnished, can fit, 100 thus permitting each of the various stops being set to any one of twelve possible circumferential positions.

a² is a lock-screw which holds the stop in 105 adjusted position (see Fig. 7) and by releasing which a stop can be moved transversely of the shaft and thus adjusted both circumferentially and longitudinally of the shaft, a quick adjustment being thus provided. To assist in effecting accurate adjustment each 110 stop is preferably furnished with an abutment screw a³ to gage the position of the line measuring devices when engaged therewith as hereinafter explained.

The shaft is rotated step-by-step to effect 115 the interchange of the stops by mechanism controlled by the line measuring mechanism re-setting key. As the machine to which the invention is shown applied is a pneumatically operated one, the line-measuring mechanism is pneumatically-controlled and the movement of the shaft B is controlled by a pneumatic motor. Conveniently there is mounted on one end of the shaft B a ratchet wheel B³ with which engages, under the influence of a spring d, the pawl D carried by a lever D' which has its pawl-carrying end resting upon a piston rod D² working in a cylinder D³.

D⁴ is a holding pawl for preventing the 130

shaft being displaced when the driving pawl D is performing its return stroke. On the operation of the special or return key at the end of the composition of a section, pressure 5 is admitted to the cylinder D³ to raise the piston rod D² to lift the lever D' and at each upward movement the lever D' and pawl D turn the wheel and shaft B through the distance of one tooth, thus interchanging 10 the stops in the path of the line-measuring element. The piston D² of the cylinder D³ on reaching the upper end of its stroke, uncovers a port d' through which air now passes by a conduit d² to the cylinder H of 15 a reversing motor for re-setting the line-measuring element. This arrangement insures that the proper stop is in position before the line-measuring element is returned.

The stops are set longitudinally of the 20 shaft to correspond with the length of the various sections of the line to be composed. They are also set circumferentially of the shaft so that as the latter is rotated at each operation, the distance of a tooth a fresh 25 stop will be interposed. In the present example there are twelve teeth on the ratchet wheel so that twelve stops can be accommodated and twelve sections composed. If the full number of stops is used, then the 30 shaft will perform a complete revolution and at the end of one series of operations be in position to commence a second series. If, however, as in the example illustrated, only three stops are needed, then it is necessary 35 to provide for the return movement of the shaft to zero or initial position after the last stop has acted. For this purpose the driving mechanism for the shaft is automatically disconnected and the shaft permitted to 40 turn to zero or initial position under the influence of the motor C the spring of which has been wound up by the forward rotation of the shaft B.

The reversing movement of the shaft is 45 governed by the controller E which is adjustably secured to the shaft B through a clutch piece E'. The piece E' has teeth e engaging similar teeth b on the end of the shaft B and is held in place by a screw cap 50 e'; it can be adjusted circumferentially of the shaft to correspond with any of the possible positions of one of the stops. For the work in hand, this controller E is set to a position corresponding with the last stop 55 to be used, so that, with the presentation of this last stop in the path of the measuring element, the controller E strikes a pin E² carried by a lever E³ mounted loosely on the shaft B or on a support concentric therewith, and shifts the said block from the position shown in Fig. 4 to that shown in Fig. 3. The lever E³ is furnished with two notches E⁴ E⁵ with one or other of which a spring pin E⁶ engages to hold the lever 65 in either of its adjusted positions.

The effect of the controller E striking the pin E² and moving the lever E³ is to cause a pin E' on the lever to engage the driving pawl D as the latter is retracted and lift it out of engagement with the ratchet wheel B³ (as shown in Fig. 6). In thus moving the tail of the pawl D depresses stem E⁸ of a valve E⁹ (see Fig. 6) to shut off the conduit e² leading from the air supply conduit e³ to the cylinder of piston D² and direct the air from the supply conduit to a conduit e⁴ leading to a cylinder E¹⁰. On the next operation, therefore, of the special or re-setting key the air in place of entering the cylinder of piston D² to advance the driving pawl, enters cylinder E¹⁰ driving out the piston E¹¹ against the tail of the holding pawl D⁴ and lifting this pawl against the action of the spring a⁶ out of gear with the ratchet wheel B³ as shown in Fig. 6. The disengagement with the ratchet wheels of pawls D and D⁴ allows the spring-motor C to rotate the shaft B in the reverse direction. Through this rotation the controller E now comes into contact with the left hand side of pin E² and shifts lever E³ back to the initial position shown in Figs. 4 and 5, where it is retained by the spring E⁶, and to prevent the lever overrunning this stop it is provided with a pin E¹² which strikes an abutment E¹³. The spring a⁶ returns the holding pawl into engagement with the ratchet wheel and a spring pin E¹⁴ returns the lever D' to its initial position.

The composing machine to which the invention is shown applied is that forming the subject matter of British Letters Patent No. 17199/08 (U. S. No. 944,405) to the specification of which attention is directed for a detailed description. It is not considered necessary here to describe this composing machine in detail, it will be sufficient to refer to the parts more intimately concerned with the present invention.

F is the motor rack of the line measuring mechanism, G the motor cylinder, H the motor return cylinder, I the units wheel which is driven from the rack F by a pinion i gearing with the teeth of the rack; J the justification indicator drum; K the justification indicator rack which gears with a pinion k² on a vertical shaft k⁴ which carries a quadrant k³ gearing with a pinion j on the spindle of the drum, the racks K and F cooperate for positioning the indicator drum. L the justification indicator drum motor, M the units rack, N the units wheel holding pawl, O the stop bars, P the line scale rack which is driven from the motor rack through the shaft of the units wheel by a pinion i', Q the justification pointer, R the resetting motor, S the line scale rack and T the bell operating lever. The stops A A' A² while acting upon the motor rack F or line-measuring element do not directly engage

this member but engage the line scale rack P, which, as stated above, is geared to the rack F. Although all the stops A A' A² may be carried on the shaft B the initial stop A^x for the line is conveniently carried on the machine frame so that it can be used when the mechanism forming the subject matter of the present invention is not in use.

The parts above referred to do not differ materially from those of the machine of the earlier patent except that the line scale S is placed to the right hand side of the machine in place of being in the center thereof and the pointer P' on the line scale rack 10 is carried on one end thereof in place of being at or about its center.

Having thus described my invention, what I claim as new is:

1. In a line measuring and justification mechanism for a key operated or manually controlled typographic composing machine the combination with a series of adjustable zero stops for the line-measuring mechanism and mechanism controlled by the initiation of the return movement of the measuring mechanism for effecting the successive adjustments of the stops, of an adjustable controller and a motor for effecting the return movement of the stops to initial position, substantially as described.
2. In a line measuring and justification mechanism for a key operated or manually-controlled typographic composing machine the combination with a series of adjustable zero-stops for the line-measuring mechanism, of mechanism controlled by a key for effecting the successive adjustments of the stops and for effecting their return to initial position, substantially as described.
3. In a line measuring and justification mechanism for a key-operated or manually controlled typographic composing machine, the combination with a series of adjustable zero-stops for the line-measuring mechanism, of a key-controlled actuating air-motor for effecting the successive interchange of the stops and a conduit controlled by the piston of the motor and leading from this motor to the reversing motor of the line-measuring mechanism, substantially as and for the purpose described.
4. In a line measuring mechanism for a key operated or manually-controlled typographic composing machine, the combination with a series of adjustable zero-stops mounted upon a rotatable shaft which is actuated by a motor driven pawl, of a controller adjustably connected to the shaft by a clutch member and arranged to operate a lever to disengage or effect the disengagement and reengagement of the shaft-driving pawl and a holding pawl, substantially as and for the purpose described.
5. In a line measuring and justification mechanism for a key-operated or manually

controlled typographic composing machine, the combination with a series of adjustable zero stops carried upon a rotatable shaft provided with pawl and ratchet mechanism D, B³ controlled by a motor D² D³, and a reversing motor C, of an adjustable controller E adapted to control the movement in both directions, of a lever which directly controls the disengagement of the driving pawl D and opens a valve to effect through a motor E¹⁰ E¹¹ the disengagement of a holding pawl D⁴, substantially as described.

6. In a composing machine such as described, provided with a line measuring mechanism including a movable member for registering the sum of space values of succeeding signals and in combination therewith a revolute shaft provided with longitudinal and circumferential series of spacing members, a stop provided with means for interlocking with both series of spacing members and means for revolving the shaft to present the stop in the path of said movable member.

7. In a composing machine such as described and in combination with the line measuring mechanism thereof, a revolute shaft provided with a series of annular grooves and circumferential spacing members, a plurality of stops each provided with interlocking means for engaging said groove and spacing members to position said stops longitudinally and circumferentially of the shaft, and means for rotating the shaft to bring the stops successively within the range of action of the line measuring mechanism.

8. In a composing machine such as described and in combination with the line measuring member thereof, a revolute shaft provided with a longitudinal series of annular grooves and circumferential recesses; a stop member provided with an elongated opening for the reception of said shaft; opposed interlocking members carried by said stop member, the one adapted to engage the annular grooves and the other the circumferential recesses, and means for rotating the shaft.

9. In a composing machine such as described, provided with a line measuring member and in combination therewith, a revolute shaft furnished with a longitudinal series of spaced annular grooves, each provided with a circumferential series of spaced recesses; a plurality of stop members encircling said shaft, each provided with an elongated opening for the shaft, interlocking members for said grooves and recesses, and an adjustable abutment for the line measuring member; and means for rotating said shaft to bring the abutments successively into the path of movement of said line measuring member.

10. In a composing machine provided

with a movable line measuring member, and in combination therewith, a variable zero positioning or stop mechanism for establishing datum lines for successive excursions of the line measuring member, the same including a reciprocating member equipped with a plurality of stops serially arranged and adapted for successive interposition in the path of the line measuring member; actuating devices for said reciprocating member including a driving pawl, an actuating piston therefor, a holding pawl and an actuating piston therefor and a return motor; a controllable pressure supply communicating with said pistons; a valve mechanism intermediate said pressure supply and pistons for alternately opening the line of communication to one and closing that to the other piston; and means for coupling said valve with the driving pawl in a manner to admit pressure to the holding pawl piston and cut-off pressure on the driving pawl actuating piston upon the withdrawal or uncoupling of said driving pawl, to effect the withdrawal of the holding pawl and permit the return of the line measuring member.

11. In a composing machine provided with a line measuring mechanism including a line measuring member and motor return mechanism therefor, and in combination therewith the following elements, to wit; a variable stop mechanism comprising a revoluble member equipped with a plurality of stops serially arranged and adapted for successive presentation to the line measuring member and a return motor; an actuating mechanism for said stop mechanism including a driving pawl, a holding pawl, a piston for advancing the driving pawl and a piston for retracting the holding pawl; a pressure supply normally in open communication with the return motor of the line measuring mechanism and with the actuating piston of the stop mechanism; and a valve mechanism adapted to open communication between the pressure supply and holding pawl piston and close communication between said pressure supply and driving pawl actuating piston.

12. A variable stop mechanism for the line measuring member of a composing machine such as described, the same including in combination, the following elements, to wit; a reciprocating member provided with a plurality of serially disposed stops; actuating devices for said reciprocating member including an intermitting driving member with an actuating piston therefor, a holding member with a retracting piston therefor, and a return motor device; a pressure supply with branches communicating with the pistons of said driving and holding members; and a valve mechanism controlling said branch lines of communication to alternately open one and close the other.

13. A variable stop mechanism for the

line measuring mechanism of a composing machine, such as described, the same including in combination, the following elements, to wit; a movable member provided with a plurality of stops serially disposed for successive presentation to the line measuring mechanism; actuating devices for said movable member including piston operated impelling means, piston released holding means and a return motor; a pressure supply conduit connected with the pistons of said impelling and holding means; and a valve controlling the lines of communication between said pistons and supply conduit the same being arranged to normally close communication with the piston of the holding means and open communication with the piston of the impelling means, and, when shifted, to cut out the piston of the impelling means and open that of the holding means, whereby when the valve is in one position, the admission of pressure in the supply conduit will actuate the impelling means to advance the movable stop member and when in another position the pressure will be applied to the holding means to release and permit the return of the stop member.

14. In a variable stop mechanism for the line measuring mechanism of composing machines, such as described, the combination of the following elements, to wit; a movable stop member equipped with a plurality of stops serially arranged for successive presentation to the line measuring mechanism; actuating means for said stop member including a return motor, piston driven actuating devices including a driving pawl and piston retracted holding devices; a pressure supply in open communication with the piston of the actuating devices; and a valve acted upon by the driving pawl when retracted and operating to close communication between the pressure supply and piston of the actuating devices and open communication between the pressure supply and the piston of the holding devices, to effect the release of the latter and the return of the movable stop member.

15. In a composing machine and in combination with the line measuring mechanism thereof, a variable stop mechanism including the following elements, to wit; a movable member provided with a plurality of stops serially arranged for successive presentation to the line measuring mechanism; actuating devices for intermittently advancing said movable member and for retracting the same including a return motor; a piston driven pawl; a holding pawl and a retracting piston for the latter; a pressure supply normally in open communication with piston of the driving pawl; a valve operated by the piston driven pawl when withdrawn from its complemental driving

member for closing communication with the driving pawl piston and opening communication with the holding pawl piston; and a controller for the driving pawl coupled with the movable member and acting upon the driving pawl to retract the latter and shift the valve.

16. In a variable stop mechanism for the line measuring devices of composing machines, the combination of the following elements, to wit; a reciprocatory member equipped with a plurality of stops serially arranged for successive presentation; actuating devices for said reciprocatory stop member including motor operated devices for intermittently advancing said member, a retaining member, and a returning motor opposing the intermitting advancing means; a motor for effecting the release of said retaining member; a pressure supply normally closed to said last named motor and open to the motor of the intermitting advancing devices for the stop member; a valve mechanism for reversing the connections between the pressure supply and the release and advancing motors to cut out the latter and energize the former; and means for actuating said valve, the same including a controller, means operated thereby for disconnecting the devices for intermittently advancing the movable stop member from the latter; and for shifting said valve, and an engaging member coupled with the reciprocatory stop member and acting upon said controller at a predetermined point in the forward traverse of said stop member.

17. In a variable stop mechanism for the line measuring mechanism of composing machines the combination of the following elements, to wit; a movable stop member equipped with a plurality of stops serially arranged for successive presentation; an actuating mechanism for said stop member including releasable driving and retaining devices and a return motor; a pressure supply with means for alternately connecting the same to said driving and retaining devices, to actuate the one or release the other; and a controller for said pressure supply shifting means adjustably coupled with the movable stop member and actuated thereby to release the driving and retaining devices of the actuating mechanism and permit the return of said movable stop member by its motor.

18. In a variable stop mechanism for the line measuring mechanism of composing machines, the combination of the following elements, to wit; a movable stop member provided with a plurality of stops serially disposed for successive presentation; actuating devices for said stop member including re-

leasable driving and retaining devices and a return motor; and means coupled with the movable stop member for automatically effecting the release of the driving and retaining devices and the return of the stop member at a predetermined point in the movement of said stop member.

19. In a variable stop mechanism for the line measuring mechanism of a composing machine, the combination of the following elements, to wit; a movable stop member provided with a plurality of stops serially arranged for successive presentation; actuating devices including a driving pawl with impelling piston, a holding pawl with releasing piston and a return motor; a controllable pressure supply communicating with the piston of the driving pawl; a valve normally closing communication between the piston of the holding pawl and the pressure supply and capable, when shifted, of opening said line of communication and closing that leading to the piston of the driving pawl; and means connected with the driving pawl for shifting said valve when said pawl is moved to uncouple the stop member.

20. In a variable stop mechanism for line measuring devices, the combination of the following elements, to wit; a movable stop member; actuating devices including a pawl and ratchet driver and a holding pawl; a controller coupled with the movable stop member and provided with a shoulder in position to engage and lift the driving pawl when said controller is moved from its normal position; and means coupled with the movable stop member and acting upon the controller to shift the latter at a predetermined point in the advance of said stop member.

21. In a variable stop mechanism for line measuring devices provided with a movable stop member and actuating devices therefor, including a reciprocatory driving pawl, and in combination therewith means controlled by the stop member for limiting the advance of the latter.

22. In a variable stop mechanism for line measuring devices equipped with a movable stop member and intermittent feed actuating devices therefor and in combination therewith means controlled by the stop member for automatically suspending the action of the feed actuating devices and means also controlled by said stop member for effecting the return of the latter to initial or zero position.
